UNITED STATES PATENT OFFICE.

BENJAMIN HAMMET TEAGUE, OF AIKEN, SOUTH CAROLINA.

ARM-REST FOR DENTISTS.

SPECIFICATION forming part of Letters Patent No. 351,079, dated October 19, 1886.

Application filed June 25, 1886. Serial No. 206,215. (No model.)

To all whom it may concern:

Be it known that I, BENJAMIN HAMMET TEAGUE, a citizen of the United States, residing at Aiken, in the county of Aiken and State of South Carolina, have invented certain new and useful Improvements in Arm-Rests for Dentists; and I do hereby declare the following to be a full, clear, and exact description of the invention, such as will enable others skilled in the art to which it appertains to make and use the same.

My invention relates to that class of rests which are used for the arm, and the object thereof is to provide means for supporting the arm of a dentist near the head of his patient while at work, for the purpose of affording protection from the pressure and weight of the arm, and supporting the latter in an uplifted position.

In the accompanying drawings, in which corresponding parts are designated by similar letters, Figure 1 represents the arm-rest in its suspended position, and Fig. 2 shows the supporting-bar detached from the arm-holder.

The arm-holder A is constructed of metal, and made of the proper width and curvilinear contour to adapt itself readily to the position of the arm of the operator. In order that the arm may be allowed entire freedom of movement, and at the same time firmly supported in any desired position, the holder A is attached, by means of the rigid buckle a, to the flexible strap C, which is provided with a series of holes for the purpose of accurately ad-

justing the height of the holder or its distance 35 from the head of the patient. This flexible strap is let into or properly secured to the lower end of the vertical pendent bar B, the upper end of which is provided with an eyelet or ring, b, which travels upon the wire or rod 40 D. The pendent bar may be secured to the horizontal supporting-rod in any desired position by means of any of the usual appliances for securing a ring upon a rod, which, being well known, need not be described. 45

Having thus described my invention, I claim and desire to secure by Letters Patent—

1. The combination of an arm-holder provided with a buckle, with a flexible strap having a suitable number of holes, whereby the 50 holder or rest is suspended at a proper height and also rendered capable of adjusting itself to the position of the arm of the operator, as herein described.

2. The combination of the arm holder or 55 rest A, provided with a buckle, a, the flexible strap C, provided with a suitable number of holes, the traveling pendent bar B, having at its upper end a ring or eyelet, and the suspended rod or wire D, as and for the purpose 60 described.

In testimony whereof I affix my signature in presence of two witnesses.

BENJAMIN HAMMET TEAGUE.
